CLAIM

The ornamental design for a seating unit, as shown and described.

DESCRIPTION

FIG. 1 is a top and side perspective view of a seating unit, showing our new design;

FIG. 2 is a view similar to FIG. 1, but showing the parts in a different position;

FIG. 3 is a side elevational view thereof;

FIG. 4 is a side elevational view thereof with the parts in a different position;

FIG. 5 is a side elevational view thereof with the parts in a still different position;

FIG. 6 is a top plan view of FIG. 5 with the cushion of one of the foot stools in raised condition; and,

FIG. 7 is an end view thereof with the cushion of one of the foot stools in raised condition.

The sides opposite those shown in FIGS. 1 and 3 are identical thereto; and the view of the end opposite that shown in FIG. 7 is identical thereto when both sides of the seating unit are in the FIG. 7 position.
